UNITED STATES PATENT OFFICE.

JOHN J. GAYNOR AND PETER CARL LIEBER, OF INDIANAPOLIS, INDIANA.

BOTTLE-CAPPING MACHINE.

1,149,821.

Specification of Letters Patent.

Patented Aug. 10, 1915.

Application filed December 15, 1913. Serial No. 806,908.

To all whom it may concern:

Be it known that we, JOHN J. GAYNOR and PETER CARL LIEBER, citizens of the United States, and residents of Indianapolis, county of Marion, and State of Indiana, have invented a certain new and useful Bottle-Capping Machine; and we do hereby declare that the following is a full, clear, and exact description thereof, reference being had to the accompanying drawings, in which like letters refer to like parts.

The object of this invention is to improve the construction of compensating mechanism in bottle capping machines in the type set forth in our applications for bottle capping machines, Serial No. 786,030, filed August 21, 1913, and Serial No. 797,554, filed October 27, 1913.

One feature of the invention consists in improvements in the compensating device for supporting the bottles and the like, and particularly means for controlling and operating the dog which initially receives the downward movement of the bottle support when the strain becomes excessive.

In a former application there is shown in the lower part of the bottle support a dog mounted so as to wedge between the fixed beveled plate and a movable beveled plate and to have frictional resistance during the entire movement thereof after the initial movement. In the present invention the dog is controlled by an upwardly pulling spring, the tension of which is adjustable and said spring holds the lower end of the dog on the beveled end of a fixed plate below, which resists the downward movement of the dog and, therefore, the bottle support until the strain becomes sufficiently great to force the lower end of the dog off said fixed plate, and thereafter there is no appreciable resistance to the downward movement of the spring support so far as these parts are concerned, but such further resistance is performed by a spring independent of said dog and fixed plate. This last-mentioned spring is a spiral spring located between the movable bottle support and fixed means on which said bottle support is mounted, so that said spring resists the downward movement of the bottle support at all times and particularly after the initial movement, and said spring also returns the bottle support and on the return said first-mentioned spring returns the dog to its normal position. There is also in the

present invention an improved means for limiting both the downward and upward movement of the bottle support.

The foregoing construction obviates irregularity of action of the dog construction shown in the previous application and particularly the irregularity of its action after the initial downward movement of the bottle support. Furthermore, in the present construction there are only two engaging surfaces in the dog construction as compared with the greater number of the frictional surfaces in the former constructions. Furthermore the compensating device can be adjusted without taking the machine apart, by adjusting the spring which controls the dog. With this construction also the resistance of the dog and fixed plate is located substantially centrally of the construction instead of to one side of the center, as in the former construction.

The full nature of the invention will be understood from the accompanying drawings and the following description and claims:

In the drawings, Figure 1 is an elevation of a portion of a bottle capping machine, with parts in section and parts omitted. Fig. 2 is a central vertical section through the bottle support and the means on which it is mounted, the lower portion of the latter being broken away and the parts shown in normal position. Fig. 3 is the same with the parts in actuated position. Fig. 4 is a section on the line 4—4 of Fig. 2. Fig. 5 is a section on the line 5—5 of Fig. 3. Fig. 6 is a perspective view of the dog and associated parts.

The drawings herein illustrate a type of bottle capping machine which is in practical use and has a base 10 and casing 11 with a driving shaft 12 and driving pinion 13 meshing with a driving gear 14 for turning the tubular bottle supports 15 and causing the rotation of an annular series of such bottle supports. Said bottle supports reciprocate their upper ends through a table 16 and centrally through said table a column 17 extends which carries the crowning head 105 plate 18.

The foregoing mechanism is old and is illustrated in our former applications and constitutes no novel part of this invention excepting in connection with the improvements hereafter set forth.

The bottle support 15, see Fig. 2, upon

which the bottle rests, has screwed on its lower end a sleeve 21 which surrounds and telescopes on the upper end of a compensating stationary tube 23 which is cylindrical and within it a rectangular tube 24 is secured. The bottle support 15 has a bar 26 extending down from it through the sleeve 21 and rectangular tube 24 and lying against the inner wall of said tube 24 and having a longitudinal recess 27 therein. Said bar 26 has in its inner side a dog recess 22 in which a dog 28 is mounted. The recess is longer than the dog, as shown in Fig. 2, and the recess has a pocket 122 in its upper end into which the beveled end of the dog projects. The lower end of the dog is beveled with the inclination downward and toward the bar 26, as shown in Fig. 3. Said dog is held in place and controlled by a spring 29 which is in the chamber 27 and is connected by a link 30 with an arm 31 extending at a right angle from the dog 28. The upper end of the spring is mounted in a bracket 120 projecting from the bar 26 by means of a threaded rod 121 which has a nut 123 on its upper end. The nut 123 is accessible by merely unscrewing the sleeve 21 and without taking the device otherwise apart and in this manner the tension of the spring 29 is regulated for a purpose hereafter explained.

A fixed plate 33 is secured to the square tube 24 by bolts 34, see Fig. 5. An additional plate 35 is located between the inner wall of the tube 24 and the fixed plate 33, and the latter is dove-tailed into the former plate, as shown in Fig. 3. The upper end of the fixed plate 33 is beveled downwardly toward the bar 26, that is, it has on its upper end an opposite bevel to the bevel on the lower end of the dog 28. When the bottle support is in its upper position, as shown in Fig. 2, the spring 29 will act on the dog 28 to throw its lower free end over upon the beveled upper end of the fixed plate 33 in such a manner that the beveled plate 33 will resist a considerable downward pressure on the bottle support. When, however, the downward pressure on the bottle support becomes sufficiently great, according to the adjustment of the spring 29, the lower end of the dog 28 will be forced laterally off the beveled upper end of the fixed plate 33, so that the dog will be forced into the recess 22 and the plate 33 will not thereafter resist the downward movement of the bottle support, and the lower limit of such downward movement is illustrated in Fig. 3. After the initial downward movement there is appreciably no resistance to farther downward movement so far as the dog 28 and beveled plate 33 are concerned.

Both the downward and upward movements of the bottle support are limited by a pin 40 which projects through the square

tube 24 into a recess 41 in the bar 26, as shown in Figs. 2 and 3. In Fig. 2, said pin is limiting the upward movement of the bottle support, and in Fig. 3, it is limiting the downward movement thereof. The return or upward movement of the bottle support is caused by a relatively heavy spring 45 which surrounds the bar 26 and lies within the stationary tube 23 with its lower end resting upon the upper end of the square tube 24 which is stationary, and the upper end bearing against a collar 46 surrounding the bar 26 and held from upward movement by a pin 146 passing through the bar 26. The spring 45 is always tending to force the bar 26 and bottle support 15 upward and, therefore, said spring 45 has two functions. It resists to some degree all downward movement of the bottle support, thus co-operating in the initial downward movement thereof with the dog 28 and the plate 33. And the other function of the spring 45 is to return the bottle support from the position shown in Fig. 3 to its upper position. This action of the spring 45, however, does not affect the spring 29 which controls the dog, as the spring 29 connects parts associated with the bar 26 at fixed distances apart.

It will be obvious from the foregoing explanation how the machine accomplishes the objects mentioned in the introduction. It might be added that by having the arms 31 projecting from the dog 28 and the connecting bar 30 pivoted thereto and pivoted to the spring 29, it causes the straight pull of the spring and, therefore, reduces the tension of the spring and since the pull of the spring is to one side of the fulcrum of the dog 28, it will tend to move the free end of the dog laterally into position on the upper end of the plate 33 and thus cause the dog to wedge in between the bar 26 and the fixed plate 33 provided with the inclined engaging surfaces which permit the dog to escape under excessive strain, and this protects the bottle on the upper end of the bottle support while being mounted. While the tubes 23 and 24 and plate 33 have been referred to as fixed or stationary, they are so called relatively to the bottle support. Means described in our former application and shown, but not described herein, at the proper time elevates and lowers the entire compensating structure. The bar 26 so far as the claims are concerned is considered a part of the bottle support as it may be integral therewith.

The invention is:

1. A bottle capping machine including a bottle support, a dog for supporting said bottle support with its lower end inclined in one direction, a fixed plate with its upper end inclined in the same direction and in position to frictionally engage the inclined

- end of the dog, and a spring for normally holding the dog on said plate.
2. A bottle capping machine including a bottle support, a dog for supporting said bottle support with its lower end inclined in one direction, a fixed plate with its upper end inclined in the same direction and in position to frictionally engage the inclined end of the dog, and a pulling spring for normally holding the dog on said plate.
3. A bottle capping machine including a bottle support, a dog for supporting said bottle support with its lower end inclined in one direction, a fixed plate with its upper end inclined in the same direction and in position to frictionally engage the inclined end of the dog, a spring for normally holding the dog on said plate, and means for adjusting the tension of said spring.
- 20 4. A bottle capping machine including a bottle support with a recess in one side thereof and a shoulder in the recess side, a relatively fixed tube in which said bottle support reciprocates, a fixed plate in said tube with its upper end beveled, a dog with its upper end bearing against the shoulder in the bottle support and its lower end beveled to fit and engage the beveled end of said fixed plate, and a spring connecting at one end with said bottle support and at its other end with said dog for moving the beveled end of the dog into engagement with the beveled end of said fixed plate.
5. A bottle capping machine including a bottle support with a recess in one side thereof and a shoulder in the recess side, a relatively fixed tube in which said bottle support reciprocates, a fixed plate in said tube with its upper end beveled, a dog with its upper end bearing against the shoulder in the bottle support and its lower end beveled to fit and engage the beveled end of said fixed plate, arms extending from said dog, and a spring pivotally connected by means of said arms with said dog at one end and at the other end connected with said
- bottle support for normally drawing the dog into an inclined position into engagement with the beveled end of said fixed plate.
- 50 6. A bottle capping machine including a bottle support with a recess in one side thereof and a shoulder in the recess side, a relatively fixed tube in which said bottle support reciprocates, a fixed plate in said tube with its upper end beveled, a dog with its upper end bearing against the shoulder in the bottle support and its lower end beveled to fit and engage the beveled end of said fixed plate, arms extending from said dog, a spring pivotally connected with said arms, a bracket extending from said bottle support, a bolt connected with said spring and operating through said bracket, and a nut on said bolt for adjusting the tension of said spring.
- 60 7. A bottle capping machine including a bottle support with a recess in one side thereof and a shoulder in the recess side, a relatively fixed tube in which said bottle support reciprocates, a fixed plate in said tube with its upper end beveled, a dog with its upper end bearing against the shoulder in the bottle support and its lower end beveled to fit and engage the beveled end of said fixed plate, arms extending from said dog, a spring pivotally connected with said arms, means mounted in connection with the bottle support for adjusting the tension of said spring, and a removable sleeve secured to the bottle support arranged so that the removal of said sleeve will render the adjusting means for said spring accessible.
- In witness whereof, we have hereunto affixed our signatures in the presence of the witnesses herein named.
